UNITED STATES PATENT OFFICE.

BERA P. HICKS, OF ASHFORD, ALABAMA.

RAIL-CLAMP.

1,180,151.

Specification of Letters Patent. Patented Apr. 18, 1916.

Application filed January 12, 1916. Serial No. 71,732.

To all whom it may concern:

Be it known that I, BERA P. HICKS, a citizen of the United States, residing at Ashford, in the county of Houston, State of Alabama, have invented certain new and useful Improvements in Rail-Clamps; and I do hereby declare the following to be a full, clear, and exact description of the invention, such as will enable others skilled in the art to which it appertains to make and use the same.

The present invention is directed to improvements in rail clamps, and has for its object to construct a device of this character which will effectually clamp the adjacent ends of rails against accidental displacement.

A further object of the invention is to provide a rail clamp having novel means for securing the rail to the tie plate, and one wherein the rails can be readily attached to or removed from engagement with a tie plate.

With these and other objects in view, this invention resides in the novel features of construction, formation, combination and arrangement of parts to be hereinafter more fully described, claimed and illustrated in the accompanying drawing, in which:—

Figure 1 is a plan view of the clamp. Fig. 2 is an end view. Fig. 3 is a sectional view on line 3—3 of Fig. 1. Fig. 4 is a plan view of the tie plate with the rails and clamping blocks removed. Fig. 5 is a side elevation of the clamp with the rails engaged therewith. Fig. 6 is a detail perspective view of one of the clamping blocks. Fig. 7 is a sectional perspective view of the tie plate. Fig. 8 is a detail view of one of the locking plates.

Referring to the drawing 1 indicates the tie plate which has formed thereon a double row of blocks 2, the adjacent sides and ends of which are spaced and provided with overhanging shoulders 3 and 4, respectively, which overhang the tie plate so as to provide longitudinal and transverse channels 5 and 6, and a central longitudinal channel 7 in which are engaged the flanges of the rails 8, said rails having their webs provided with openings 9, the purpose of which will appear later.

A plurality of clamping blocks 10 are provided, which have their lower surfaces provided with spaced lugs 11 which have their sides provided with inclined shoulders 12

which are adapted to engage the overhanging shoulders 4 of the blocks 2 when said lugs are engaged in the transverse channels 6. The inner ends of the blocks 10 are provided with tenons 13 which are adapted to engage in the openings 9 formed in the webs of the rails 8. After the blocks 10 are engaged in the respective channels 6, the locking plates 14 are engaged in the longitudinal channels 5, said plates having inclined side edges 15 which are adapted to engage the overhanging shoulders 3 formed in the sides of the blocks 2.

It will be noted that the locking plates 14 engage in the spaces between the lugs 11 of the clamping blocks 10, thus preventing accidental removal of the same. The locking plates 14 are further provided with spike openings 16 which are adapted to register with the openings 17 formed in the tie plate 1, whereby when the spikes are driven through the registered openings, the locking plates are held against accidental removal.

From the foregoing description it will be seen that a rail clamp has been provided which is constructed in such a manner that the rails can be firmly clamped with their meeting ends in abutting relation, and readily disengaged from the clamp when it is desired to replace the rails.

What is claimed is:—

1. A rail clamp comprising a tie plate, said plate having formed thereon outer longitudinal channels and a central longitudinal channel, transverse channels intersecting the longitudinal channels, said central channel being adapted to receive the meetings ends of the pair of rails, blocks removably engaged in the transverse channels and having their inner ends engaged with the webs of the rails, and means slidably engaged in the outer longitudinal channels for engaging the locking blocks to prevent accidental removal from the respective channels.

2. A rail clamp comprising a tie engaging plate, said plate having formed thereon longitudinally arranged blocks, said blocks being arranged in rows to provide outer channels, and an intermediate channel, transverse channels intersecting the longitudinal channels, the adjacent sides and ends of said blocks having inclined shoulders which overhang the plate, the central channel being adapted to be engaged by the meeting ends of the rails, locking blocks

having spaced lugs formed on their under surfaces, said lugs having inclined shoulders for engaging the similar shoulders of the transverse channels, said locking blocks 5 having their inner ends engaged with the webs of the rails, and locking plates slidably engaged in the outer longitudinal channels and in the spaces between said lugs to pre-

vent accidental withdrawal of the locking blocks.

In testimony whereof, I affix my signature, in the presence of two witnesses.

BERA P. HICKS.
